(57) CLAIM

The ornamental design for a sports folder, as shown and described.

DESCRIPTION

FIG. 1 is a top plan view of a sports folder showing my new design in a closed condition;

FIG. 2 is a bottom plan view of FIG. 1;

FIG. 3 is a front elevational view of FIG. 1;

FIG. 4 is a rear elevational view of FIG. 1;

FIG. 5 is a left side elevational view of FIG. 1, the right side being a mirror image thereof;

FIG. 6 is a top plan view of FIG. 1 in an opened condition;

FIG. 7 is a top plan view of a second embodiment of my design of FIG. 1;

FIG. 8 is a bottom plan view of FIG. 7;

FIG. 9 is a front elevational view of FIG. 7;

FIG. 10 is a rear elevational view of FIG. 7;

FIG. 11 is a left side elevational view of FIG. 7, the right side being a mirror image thereof; and,

FIG. 12 is a top plan view of FIG. 7 in an opened condition. The note pad depicted by means of broken lines in the figures has been shown for illustrative purposes only and forms no part of the claimed design.
